DESIGN FOR A LETTER TRAY OR ANALOGOUS ARTICLE

Roscoe W. Clark, Lakewood, N. Y., assignor to Art
Metal Construction Company, Jamestown,
N. Y.

Application February 4, 1943, Serial No. 109,445

Term of patent 14 years

To all whom it may concern:

Be it known that I, Roscoe W. Clark, a citizen of the United States, residing at Lakewood, Chautauqua County, State of New York, have invented a new, original, and ornamental Design for a Letter Tray or Analogous Article, of which the following is a specification, reference being had to the accompanying drawing forming a part thereof.

In said drawing:

Fig. 1 is a perspective view of a letter tray embodying my design.

Fig. 2 is a plan view thereof.

Figs. 3 and 4 are respectively side and end elevations of the tray.

I claim:

The ornamental design for a letter tray or analogous article, substantially as shown.

ROSCOE W. CLARK.
